(57) **CLAIM**

The ornamental design for a lamp-type projector, as shown and described.

DESCRIPTION

FIG. 1 is a perspective view of a lamp-type projector showing my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof; and,

FIG. 8 is a rotated side view thereof combined with a lamp holder.

The lamp holder is shown in broken lines for illustrative purposes only, and forms no part of the claimed design.
